MONOQUATERNARY AMMONIUM CARBONATES AND THEIR PREPARATION

James H. Werntz, Wilmington, Del., assignor to
E. I. du Pont de Nemours & Company, Wil-
mington, Del., a corporation of Delaware

No Drawing. Application November 15, 1949,
Serial No. 127,520

17 Claims. (Cl. 260—244)

1

This invention relates to quaternary ammonium salts and, more particularly, to quaternary ammonium carbonates and to methods for their preparation.

Although considerable technical interest in quaternary ammonium salts and their corresponding bases has developed in recent years, quaternary ammonium salts of the very weak acids, notably monoquaternary ammonium salts of carbonic acid, have remained unknown.

It is an object of this invention to provide monoquaternary ammonium salts of carbonic acid. A further object is to provide a novel method for the production of quaternary ammonium carbonates. Other objects will appear hereinafter.

These objects are accomplished by this invention which comprises certain new quaternary ammonium carbonates and a process for their production which comprises reacting, preferably in the presence of an alcohol, at a temperature within the range of 100° C. up to the decomposition point of the resulting quaternary ammonium carbonate, a tertiary monoamine, i. e., a trialiphatic amine which, exclusive of amino nitrogen, is aliphatic acyclic hydrocarbon, with a dialiphatic hydrocarbon ester of carbonic acid which, exclusive of the carboxyldioxy radical,

is aliphatic acyclic hydrocarbon. For use in this invention preferred tertiary amines are trialiphatic saturated acyclic hydrocarbon amines and the preferred dialiphatic esters of carbonic acid are dialiphatic saturated acyclic hydrocarbon esters of carbonic acid.

The new monoquaternary ammonium carbonates of this invention are those having the anion of a monoaliphatic acyclic hydrocarbon ester of carbonic acid attached through oxygen to the quaternary nitrogen atom, the remaining four valences of said quaternary nitrogen atom being bonded to aliphatic acyclic hydrocarbon radicals, at least three of which are monovalent aliphatic acyclic hydrocarbon radicals. Preferred monoquaternary ammonium carbonates are those having the anion of a monoaliphatic saturated acyclic hydrocarbon ester of carbonic acid attached through oxygen to the quaternary nitrogen atom, the remaining four valences of said quaternary nitrogen atom being bonded to aliphatic saturated acyclic hydrocarbon radicals, at least three of which are monovalent aliphatic saturated acyclic hydrocarbon radicals. These new mono-

2

quaternary ammonium carbonates can be represented by the formula:

or

wherein the R's are monovalent aliphatic acyclic hydrocarbon radicals, preferably alkyl radicals of 1 to 18 carbon atoms, and R' is an aliphatic acyclic hydrocarbon radical which is a monovalent aliphatic acyclic hydrocarbon radical, preferably alkyl of 1 to 6 carbon atoms, or the divalent ethylene, $-\text{CH}_2-\text{CH}_2-$, radical having its two valences bonded respectively to the quaternary nitrogen atom and to one of the valences of the carboxyldioxy radical,

25 to form a six-membered heterocyclic ring, i.e.

The following equation with a typical tertiary amine and diester of carbonic acid represents the 35 reaction in the process of this invention:

40 In actual practice the preparation of the quaternary ammonium carbonates of this invention can be carried out by charging into a suitable reactor the selected trialiphatic tertiary amine, for example triethylamine, and the dialiphatic ester of carbonic acid, for example diethyl carbonate and, if desired an alcohol such as ethanol. The reaction vessel is closed and then heated under autogenous pressure at a suitable temperature, 45 preferably in the range of 150° to 180° C., for about 6 to 20 hours with agitation. After completion of the reaction, the reactor is cooled, opened and the contents are discharged. The product is then isolated by removal, through distillation, of the solvent, if present, and of any unreacted reagents.

55

3

The mole ratio of tertiary amine to dialkyl carbonate may vary between 10:1 to 1:10. Best results are achieved, however, with a mole ratio of 2:1 to 3:1. The use of alcoholic solvents ordinarily gives superior results, the preferable mole ratio of alcohol to tertiary amine being about 5:1, although mole ratios of 1:1 to 15:1 can also be satisfactorily employed.

Since the time necessary to complete the reaction decreases with increasing temperature, it is desirable, though not essential, to operate at a temperature as high as possible below the decomposition temperature of the quaternary ammonium carbonate formed. In general, the temperature range of 150 to 180° C. has been found the most satisfactory although the reaction may be carried out at a temperature as low as 100° C. Depending on the temperature and reagents employed as well as the presence of solvent, the time of reaction varies from 6 to 20 hours although at 150 to 180° C., 8 to 12 hours reaction time is usually satisfactory.

The invention is illustrated in further detail by the following examples in which parts, unless otherwise specified, are given by weight.

Example I

A mixture of 20.2 parts of triethylamine, 4.5 parts of dimethylcarbonate (boiling point 89-91° C.) and 16 parts of methanol was heated in a sealed glass tube for 8 hours at 170° C. After removal of the methanol and unreacted triethylamine and dimethylcarbonate by heating on a steam bath under reduced pressure, 5.2 parts of brown solid triethylmethylammonium methyl carbonate was obtained. This quaternary ammonium carbonate is soluble in water and hygroscopic. It liberates carbon dioxide when dissolved in aqueous acid solutions. The product analyzed by the Knorr method shows 28.88% of carbonate (CO₃) as compared to the theoretical value of 31.4% calculated for

Example II

Employing the procedure of the above example, 40 parts of triethylamine, 12 parts of dimethyl carbonate, and 40 parts of methanol yielded 7 parts of triethylmethylammonium methyl carbonate.

Example III

The triethylmethylammonium methyl carbonate (3.3 parts) was also obtained without the methanol solvent by the same procedure as described in Example I from 32 parts of triethylamine and 7.2 parts of dimethyl carbonate.

Example IV

A mixture of 20.2 parts of triethylamine, 5.9 parts of diethyl carbonate and 16 parts of methanol was heated at 170° C. in a sealed glass reactor for 8 hours. The reaction product was then heated at 100° C. under about 15 mm. pressure to remove the unreacted tertiary amine and dialkyl carbonate. The residual tetraethylammonium ethyl carbonate (2.4 parts), a brown, hygroscopic oil, soluble in water, liberated carbon dioxide when dissolved in aqueous acid solution. Analysis by the Knorr method showed 28.9% carbonate as compared to the calculated value of 27.4% for carbonate (CO₃) in

4

Example V

Fifteen (15) parts of octadecyldimethylamine, 18 parts of dimethyl carbonate and 32 parts of methanol were heated in a sealed glass reactor for eight hours at 170° C. After removal of volatile material by heating on the steam bath under reduced pressure (about 5 mm.), 18.5 parts of octadecyltrimethyl ammonium methyl carbonate was obtained. This product, soluble in water, gave clear, strongly sudsing solutions. It analyzed for 3.78% nitrogen as compared to a calculated value of 3.62% for the above product.

Example VI

Cyclic ethylene carbonate,

F. P. 36° C.; B. P. 248° C., 10.1 parts, was reacted with 46.5 parts of triethylamine in the presence of 37 parts of methanol at 170° C. for about 8 hours. After removal through distillation of the solvent, unreacted amine and cyclic ester from the reaction mixture, there was obtained 9.8 parts of hygroscopic, viscous, brown, water-soluble, oily cyclic carbonate of triethyl-2-hydroxyethylammonium hydroxide having the structural formula

Analysis of the product showed a nitrogen content of 5.8%.

This invention is not limited to the specific reactants illustrated in the foregoing examples, but embraces more broadly the reaction of a tertiary monoamine, i. e., a trialiphatic acyclic hydrocarbon amine, with a dialiphatic acyclic hydrocarbon ester of carbonic acid. The tertiary monoamines employed in the process of this invention are those having only monovalent aliphatic acyclic hydrocarbon radicals, i. e., saturated and unsaturated acyclic hydrocarbon radicals, of up to 22 carbon atoms attached to the amino nitrogen. Because of availability and suitable reactivity the trialiphatic tertiary amines in which the monovalent aliphatic acyclic hydrocarbon radicals are alkyl of up to 18 carbon atoms are preferred. Additional examples of these tertiary amines include tripropylamine, triisopropylamine, triisobutylamine, tri-n-butylamine, tri-n-amylamine, tri-n-octylamine, dimethylodecylamine, diethylallylamine, dimethyloleylamine, dimethyldecosylamine, and the like.

The carbonates, i. e., the dialiphatic acyclic hydrocarbon esters of carbonic acid, which can be employed in this process are those in which the two valences of the carboxyl radical,

are bonded to aliphatic acyclic hydrocarbon radicals, preferably two monovalent alkyl radicals of up to 6 carbon atoms or the divalent ethylene radical, —CH₂—CH₂—. Examples include dimethyl carbonate, diethyl carbonate, dipropyl carbonate, dibutyl carbonate, diisobutyl carbonate, diethyl carbonate, diisopropyl carbonate,

cyclic ethylene carbonate, and the like. Thus, by the process described herein can be prepared tetra-n-butyl ammonium butyl carbonate, from tri-n-butylamine and di-n-butyl carbonate, dodecyltrimethyl ammonium methyl carbonate from dimethyldecylamine and dimethyl carbonate, and triethyl-1-ethyl-butyl ammonium 1-ethylbutyl carbonate from triethylamine and bis-(1-ethylbutyl) carbonate.

In the process of this invention, the use of alcoholic solvents, particularly the monohydric alcohols, for example, alkanols, cycloalkanols and aralkanols of up to 7 carbon atoms, usually give superior results. When processing the aliphatic tertiary amines which contain at least one monovalent aliphatic acyclic hydrocarbon group of at least six carbon atoms, it is preferred to operate in the presence of these alcohols. Examples of monohydric hydrocarbon alcohols which may be used include methanol, ethanol, propanol, isopropanol, isobutanol, n-butanol, cyclohexanol, benzyl alcohol, and the like. Methanol, ethanol and benzyl alcohol are preferred.

The quaternary ammonium salts of this invention are appreciably water-soluble and useful as antistatic agents for textile yarns. Those quaternary ammonium carbonates which contain at least one monovalent aliphatic acyclic hydrocarbon radical, especially an alkyl radical, of six or more carbon atoms attached to the quaternary nitrogen atom are particularly desirable and preferred in this respect. The quaternary ammonium salts of this invention are also important intermediates for the preparation of quaternary ammonium bases, being readily converted to these on treatment with alkaline earth hydroxides, e. g., barium hydroxide and calcium hydroxide.

As many apparently widely different embodiments of this invention may be made without departing from the spirit and scope thereof, it is to be understood that this invention is not limited to the specific embodiments thereof except as defined in the appended claims.

I claim:

1. A monoquaternary ammonium carbonate having the formula

wherein the (R)'s are monovalent aliphatic hydrocarbon radicals of from 1 to 22 carbon atoms from the group consisting of alkyl radicals and alkenyl radicals containing one ethylenic bond only, and at least two of the (R)'s are alkyl radicals, and the (R)'s are selected from the group consisting of alkyl radicals of from 1 to 6 carbon atoms and the methylene radical, the latter being joined together and to the nitrogen and oxygen atoms to form a six-membered heterocyclic ring.

2. A monoquaternary ammonium carbonate having the formula

wherein the (R)'s are alkyl radicals of from 1 to 18 carbon atoms and the (R)'s are alkyl radicals of from 1 to 6 carbon atoms.

3. A monoquaternary ammonium carbonate having the formula

10 wherein the (R)'s are alkyl radicals of from 1 to 18 carbon atoms.

4. Triethylmethylammonium methyl carbonate.

5. Tetraethylammonium methyl carbonate.

6. Octadecyltrimethylammonium methyl carbonate.

7. The cyclic carbonate of triethyl-2-hydroxyethylammonium hydroxide having the formula

13. A process as set forth in claim 12 wherein said amine and said cyclic ethylene carbonate are heated in a monohydric alcohol solvent of from 1 to 7 carbon atoms.

14. A process for preparing triethylmethylammonium methyl carbonate which comprises heating at a temperature within the range of 150-180° C., triethylamine and dimethyl carbonate in a monohydric alcohol solvent of from 1 to 7 carbon atoms.

15. A process for preparing tetraethylammonium ethyl carbonate which comprises heating at a temperature within the range of 150-180° C., triethylamine and diethyl carbonate in a monohydric alcohol solvent of from 1 to 7 carbon atoms.

16. A process for preparing octadecyltrimeth-

ylammonium methyl carbonate which comprises heating at a temperature within the range of 150-180° C., octadecyltrimethylamine and dimethyl carbonate in a monohydric alcohol solvent of from 1 to 7 carbon atoms.

17. A process for preparing the cyclic carbonate of triethyl-2-hydroxyethylammonium hydroxide which comprises heating at a temperature within the range of 150-180° C., triethylamine and cyclic ethylene carbonate in a monohydric alcohol solvent of from 1 to 7 carbon atoms.

JAMES H. WERNTZ.
